PROCESS OF PRODUCING INVISIBLE WRITING

John Wesley McCulloch and Chester H. Myers,
Monroe, Oreg.No Drawing. Application March 1, 1937,
Serial No. 128,547

2 Claims. (Cl. 41—20)

Our invention relates generally to means for producing invisible writing on surfaces, and particularly to a process of treating a sheet of paper or the like to produce invisible writing thereon, 5 which writing can be restored to visibility at will and rendered again invisible, and an important object of our invention is to provide a process of this character which is simple, efficient, and inexpensive and wherein a permanent record is 10 available.

Other important objects of our invention will be apparent from a reading of the following description taken in connection with the example given for illustrative purposes.

15 The process of the present invention contemplates the production of invisible but restorable writing upon sheets of ordinary paper, so that the sheets may be utilized as and stored as permanent records in which the invisible writing may 20 be restored at any desired future time and again rendered invisible.

25 The embodiment of the present invention contemplates a process wherein an ordinary sheet of white typewriting or other writing paper is placed in a basin or trough containing water and permitted to remain in the water for about five minutes or until the same becomes thoroughly soaked and wet through, so as to produce what is herein-after referred to as "wet sheet".

30 This "wet sheet" is then placed on a glass or other suitable smooth and polished surface of non-absorbent character, and on this "wet sheet" so imposed on the supporting surface, is placed a dry sheet of paper similar in size and constitution to the sheet from which the "wet sheet" is produced, and in substantial registry with the "wet sheet".

35 An ordinary lead pencil or other suitable writing stylus is then taken and used to write in the ordinary way on the dry sheet. When this writing is completed, the dry sheet is removed and may be destroyed, since it is then of no further use in the process.

The "wet sheet" indented by the writing is then 40 taken from the glass supporting surface and placed between two pieces of white absorbent cloth, such as ordinary dish towels, so that a goodly proportion of the superficial moisture in the "wet sheet" and on the surface thereof is absorbed by contact with the absorbent cloths.

45 After the "wet sheet" has been placed as described between the two pieces of absorbent cloth, the assembly is placed on a suitable supporting surface and a medium hot sadiron or other equivalent ironing instrument is applied to the top cloth and the assembly ironed until the moisture in the "wet sheet" has been dissipated and the

writing indentations on the wet sheet entirely disappear.

The resultant "wet sheet" which is no longer wet, can in this processed condition be either stored or mailed or otherwise handled.

5 When it is desired to cause the writing on the "wet sheet" to reappear, this "wet sheet" is placed in a basin or trough of water, whereupon, after elapse of a short time, the original writing on the "wet sheet" will become visible.

10 After the writing has been caused to re-appear and the purpose of such reappearance having been served, the "wet sheet" can then be put away to dry and the writing will disappear again.

15 Thereafter whenever it is desired to cause the writing to become visible the "wet sheet" is placed in water as described above. The production of the appearance and the production of the disappearance of the writing may be repeated an indefinite number of times with the same "wet 20 sheet".

25 Although we have shown and described herein a preferred embodiment of the process of our invention, it is to be definitely understood, that we do not desire to limit the application of the invention thereto, and any change or changes may be made in the sequence and duration of steps and operations, within the spirit of the invention and the scope of the subjoined claims.

Having described the invention what is claimed 30 as new is:—

1. A process of producing invisible writing on a sheet and restoring such writing to visibility, said process comprising thoroughly wetting said sheet, then placing the resultant "wet sheet" on a supporting surface and on the "wet sheet" then imposing a dry sheet, then writing on said dry sheet in a manner to indent said "wet sheet", then drying said "wet sheet" so as to cause the writing to disappear; and then wetting the dried 35 "wet sheet" so as to cause the writing to reappear.

2. A process of producing invisible writing on a sheet and restoring such writing to visibility, said process comprising thoroughly wetting said sheet, then placing the resultant "wet sheet" on a supporting surface and on the "wet sheet" then 45 imposing a dry sheet, then writing on said dry sheet in a manner to indent said "wet sheet", then drying said "wet sheet" so as to cause the writing to disappear; and then wetting the dried "wet sheet" so as to cause the writing to appear, said 50 drying being accomplished by ironing the wet "wet sheet" between absorbent sheets until said "wet sheet" is dry and the writing thereon has disappeared.
